BY

UNITED STATES PATENT OFFICE.

JOSEPH GOODMAN, OF WHITNEYVILLE, CONNECTICUT, ASSIGNOR TO THE MT. CARMEL MANUFACTURING COMPANY, OF MOUNT CARMEL, CONNECTICUT, A CORPORATION OF CONNECTICUT.

ADJUSTABLE ESCUTCHEON.

Application filed May 25, 1925. Serial No. 32,605.

To all whom it may concern:

Be it known that I, JOSEPH GOODMAN, a citizen of the United States, residing at Whitneyville, county of New Haven, State of Connecticut, have invented a new and useful Adjustable Escutcheon, of which the following is a specification.

This invention relates to door handles, and especially to the type of door operating handles used on automobiles, and has for an object to provide an improved and simple construction which will allow for angular adjustment of the escutcheon on the shank of the handle, so that when applied to the door it will lie flush with the surface thereof regardless of the angle at which the spindle extends through the door.

With the foregoing and other objects in view, I have devised the construction illustrated in the accompanying drawing forming a part of this specification, similar reference characters being employed throughout the various figures to indicate corresponding elements. In this drawing, Fig. 1 is a transverse section through a portion of a door showing my improved handle attached thereto, the handle being shown in elevation.

Fig. 2 is a transverse section substantially on line 2—2 of Fig. 1.

Fig. 3 is an edge elevation of the type of washer used in the construction of Fig. 1.

Fig. 4 is a bottom plan view thereof.

Fig. 5 is a rear elevation of the escutcheon shown in Fig. 1.

Fig. 6 is a transverse section thereof substantially on line 6—6 of Fig. 5.

Fig. 7 is a section through the escutcheon showing a portion of the shank and handle in elevation, and showing a slightly different construction of the connection between the shank and the escutcheon.

Fig. 8 is a section through the construction of Fig. 7 taken substantially at right angles to the plane of the section of Fig. 7.

Fig. 9 is a side elevation of the washer used in Figs. 7 and 8.

Fig. 10 is a plan view thereof.

Fig. 11 is a view similar to Fig. 8 showing a slightly different construction.

Fig. 12 is a side elevation of the washer used in Fig. 11.

Fig. 13 is a plan view thereof.

Fig. 14 is a view similar to Fig. 8 showing how my invention may be applied to a sheet metal escutcheon, and

Fig. 15 is a rear elevation thereof.

Referring to the device shown in Figs. 1 to 6 inclusive, 16 represents the door of an automobile having any desired form of latch, not shown which is operated by a handle 17 on the outside of the door. Connected with this handle is a spindle 18 extending through the escutcheon 19 and includes the usual square portion 20 which extends into the latch mechanism in the usual and well-known manner. The escutcheon is secured to the door by suitable screws 21. It very often happens that the outer surface of the door is not at right angles to the axis of the spindle when it is applied to the latch in the proper position for operating the same. Therefore, if the escutcheon is rigid on the spindle either it will not lie flush with the surface of the door or the spindle will be cramped in the latch mechanism. To obviate this objection I have provided an improved connection between the escutcheon and the spindle which will allow the escutcheon to rock in any direction on the spindle and will, therefore, lie flush with the surface of the door no matter how this door may be shaped.

The escutcheon is provided with an opening 22 through which the spindle extends and this opening is of a greater diameter than the spindle to allow clearance for the rocking movement of the escutcheon. There is a pair of spaced abutments on this spindle between which the escutcheon is located. The outer abutment 23 may be a shoulder formed on the spindle or may be formed in a separate element 24 as in the present construction, and the inner surface 23 of this element is concave to fit the convex surface on the outward extension of the escutcheon 26. The abutment on the opposite side of the escutcheon is formed by the ring member 27 which may be secured to the spindle in any suitable manner desired. A convenient means is by soldering it to the spindle. Between this abutment and the escutcheon is a member 28 which has pivotal connection with the escutcheon on opposite sides of the spindle about which the escutcheon may rock in one plane, and

this member 28 also has pivotal connection with the abutment 27 on opposite sides of this spindle, but intermediate the pivotal connections with the escutcheon, about which the escutcheon may rock in another plane. For best results these two pairs of pivotal connections are located in planes at substantially right angles to each other. By this arrangement the escutcheon may rock not only in the planes of the pivotal connections but also in the intermediate planes so that this escutcheon has universal angular adjustment on the spindle and may assume a position corresponding to the inclined surface of the door.

These pivotal connections in different planes may be provided in a number of different ways. In Fig. 1 the member 28 comprises a washer bent laterally or offset at four points spaced substantially ninety degrees apart to form diametrically positioned lugs 29 and 30. Two of these lugs are spaced laterally from the plane of the other two, or in other words, two opposite lugs are offset at a greater distance than the other pair so that when placed in position the pair which is the more offset, as 29, will engage the surface of the stop or ring 27, but the other pair 30 will be spaced from this surface as shown in Fig. 6, and therefore, this member 28 can rock about the lugs 29 as pivots. In this particular construction the escutcheon is provided with a pair of lugs 31 seated in the concave sides of the lugs 30, as shown in Fig. 6, and these lugs are of such a length that the escutcheon is spaced from the body portion of the member 28 and may rock about the pivots formed by the lugs 31. The lugs 31 and 30 are arranged intermediate the lugs 29, preferably the line joining them being at right angles to the line joining the lugs 29. It will be apparent from this construction that the escutcheon may rock about the pivots 30-31 in one plane and about the pivots 29 in another plane disposed at an angle to the first plane, in the present construction substantially at the right angles, and by rocking about both set of pivots simultaneously it can rock in a plane at any intermediate angle, so that the escutcheon may rock in any plane transverse to the spindle and will have practically universal adjustment thereon.

This construction may also be used with a locking mechanism for locking the handle and spindle against turning. For this purpose the escutcheon may be provided with a plurality of notches 32 and there may be a laterally sliding bolt 33 mounted in the spindle with a key controlled cylinder 34 connected to this bolt for sliding it in and out in the spindle and projecting its free end into one of the notches 32 to lock the spindle, or retracting it therefrom to unlock

it, as will be obvious. The keyhole or slot leading to the cylinder 34 is exposed on the outer surface of the handle.

The construction shown in Figs. 7 and 8 is the same as that shown in Figs. 1 to 6 as far as the rocking movement of the escutcheon is concerned except that it is reversed. In this arrangement the lugs 29' having the greater offset rest against and pivot on the shoulder 35 of the escutcheon 36, while the lugs 37 corresponding to the lugs 31 on the escutcheon in the first form are located on a collar 38 forming an abutment on the spindle and these lugs 37 are seated in the concave sides of the lugs 30'. The effect and operation is the same as in the first form, the escutcheon rocking about the lugs 29' in one plane and about the lugs 37 in another plane, and by rocking about both of them it may rock in any intermediate plane, the same as in the first form. The collar 38 is prevented from sliding longitudinally on the spindle 18 by any suitable means such as a ring 39 soldered to the spindle. In this particular construction, however, the lugs 29' and 30' are not offset different amounts but are offset practically the same amount, while the shoulder 35 of the escutcheon is provided with two sets of notches 40 and 41, in which notches 40 the lugs 29' are seated. The lugs 30' extend into notches 41 but these notches are deeper than the notches 40 to allow for the rocking movement of the member 28'. The collar 38 may turn relative to the spindle and therefore, when the spindle is turned in the escutcheon the member 28' and the collar will be held stationary by the notches 40 and the lugs 37. It will, of course, be apparent that as the escutcheon rocks about these pivots the convex surface 25 will slide in the concave surface 23, and to facilitate this movement these surfaces are preferably made spherical.

In figs. 11, 12 and 13, I have shown a slightly different arrangement. In this form the escutcheon has an annular shoulder 42 on the opposite side from the curved surface 25, and the inner abutment is formed by a ring 43, the same as the ring 37 in the first form. The intermediate member 44, however, instead of having the four lugs or offsets extending laterally from the body portion thereof in the same direction has two diametrically arranged lugs or offsets 45 extending laterally to one side and two diametrically arranged lugs or offsets 46 extending laterally from the opposite side and intermediate the first two lugs or offsets. The offsets 45 engage the shoulder 42 on the escutcheon and the escutcheon may, therefore, rock on these two offsets. The offsets 46 engage the abutment or shoulder formed by the ring 43 and the member may, therefore, rock on this ring about these lugs

or offsets as pivots, but in a plane at an angle to the plane in which the escutcheon rocks about the lugs or offsets 45. The effect, however, is the same as in the first 5 case and the escutcheon may rock about the spindle in any plane desired.

In Figs. 14 and 15, I have shown this invention arranged for use with an escutcheon made of sheet metal. In this form the 10 escutcheon 47 is stamped from sheet metal and is laterally offset to form a flange 48 convex on its outer surface to engage the concave surface or abutment 49 on the spindle. A flat washer 50 engages the opposite side of the escutcheon to form a shoulder corresponding to the shoulder 42 of the escutcheon shown in Fig. 11, and the intermediate member 44 is of the same construction and arrangement as that shown in 15 Figs. 11, 12 and 13. The lugs or offset 45 on this member engage the washer or plate 50 so that the escutcheon may rock on these lugs or offsets and the lugs or offsets 46 engage the ring 51, the same as in the form 20 shown in Fig. 11, so that the escutcheon and the member 44 may rock on these lugs or off-sets as pivots, the ring 51 being secured to the spindle by soldering or any other suitable means. It will be noted that the 25 operation in this form is the same as in the other form and the washer or plate 50 is in effect a part of the escutcheon and has the same effect as if it were actually a part of the escutcheon. In fact, it could be 30 soldered to the escutcheon in which case it would be in one piece therewith.

It will be apparent from the foregoing 35 description that with this construction I am enabled to secure a universal angular adjustment of the escutcheon on the handle and spindle, and that I secure this adjustment with an extremely simple construction requiring a minimum number of parts. It can, therefore, be manufactured at relatively 40 low cost and is easily assembled, and is not likely to be easily gotten out of order in 45 operation.

Having thus set forth the nature of my 50 invention, what I claim is:

1. In a device of the character described, 55 an escutcheon adapted to be secured to a door and having an outwardly extending flange provided with a convex outer surface, a handle having a spindle extending through said escutcheon, spaced abutments on the spindle one of which engages said convex surface, and means between the other abutment and the escutcheon providing a plurality of spaced pivots between the escutcheon and the abutment located about the spindle to allow universal angular adjustment of the escutcheon.

2. In a device of the character described, 60 an escutcheon adapted to be secured to a door and having an outwardly extending

flange provided with a convex outer surface, a handle having a spindle extending through said escutcheon, spaced abutments on the spindle one of which engages said convex surface, and means between the other abutment and the escutcheon having pivotal connection with the escutcheon in one plane and also pivotal connection with the abutment in another plane at an angle to the plane of the first pivot. 70

3. In a device of the character described, a door handle having a spindle, spaced abutments on said spindle, an escutcheon between said abutments having engagement with one of the abutments, and means between the escutcheon and the other abutment having rocking engagement with the escutcheon in one plane and rocking engagement with the abutment in another plane at an angle to the first plane. 75

4. In a device of the character described, a door handle having a spindle, spaced abutments on said spindle, an escutcheon between said abutments having engagement with one of the abutments, and means between the escutcheon and the other abutment having pivot bearings with the escutcheon on opposite sides of the spindle and pivot bearings with the abutment on opposite sides of the spindle in a plane at substantially right angles to the plane of the first pivots. 80

5. In a device of the character described, a door handle having a spindle, spaced abutments on said spindle, an escutcheon between said abutments having engagement with one of the abutments, and a washer between the escutcheon and the other abutment, said washer having spaced pivot bearings with the escutcheon on opposite sides of the spindle and also spaced pivot bearings with the abutment on opposite sides of the spindle intermediate the first bearings. 100

6. In a device of the character described, 105 an escutcheon adapted to be secured to a door and having an outwardly extending flange provided with a convex outer surface, a handle having a spindle extending through said escutcheon, spaced abutments on the spindle one of which engages said convex surface, and a washer between the escutcheon and the other abutment having spaced pivotal connections with the escutcheon on opposite sides of the spindle and also spaced pivotal connections with the abutment on opposite sides of the spindle intermediate the first pivotal connections. 110

7. In a device of the character described, 115 a door handle having a spindle, spaced abutments on said spindle, an escutcheon between said abutments having engagement with one of the abutments, and means between the escutcheon and the other abutment providing spaced pivots between the escutcheon and the abutment located about the spindle to allow angular adjustment of the 120

escutcheon in a plurality of different planes.

8. In combination, an escutcheon adapted to be secured to a door, a latch operating handle having a spindle extending through the escutcheon, abutments on the spindle on opposite sides of the escutcheon, one of said abutments being concave and the escutcheon having a convex surface in engagement therewith, and a member between the escutcheon and the other abutment, said member having rocking connections with the escutcheon on opposite sides of the spindle and also rocking connections with the abutment on opposite sides of the spindle but intermediate the first connections.

9. In combination, an escutcheon adapted to be secured to a door, a latch operating handle having a spindle extending through the escutcheon, abutments on the spindle on opposite sides of the escutcheon, one of said abutments being concave and the escutcheon having a convex surface in engagement therewith, and a member between the escutcheon and the other abutment, said member having spaced pivotal engagement with the escutcheon on opposite sides of the spindle about which the escutcheon may rock in one plane and spaced pivotal engagement with the abutment intermediate those with the escutcheon about which the escutcheon may rock in another plane.

10. In a device of the character described, a door handle having a spindle, spaced abutments on said spindle, an escutcheon between said abutments having engagement with one of the abutments, and a washer between the escutcheon and the other abutment, said washer being provided with two pairs of spaced laterally extending projections forming pivotal connections with the escutcheon and abutment about which the escutcheon may rock in different planes.

11. In a device of the character described, a door handle having a spindle, spaced abutments on said spindle, an escutcheon between said abutments having engagement with one of the abutments, a member between the escutcheon and the other abutment, said member having a pair of diametrically positioned lugs extending from one side thereof to engage the abutment to form pivots about which the member may rock, said member being also provided with recesses on the other side intermediate the lugs, and projections on the escutcheon seated in said recesses and forming pivots about which the escutcheon may rock.

12. In a device of the character described, a door handle having a spindle, spaced abutments on said spindle, an escutcheon member between said abutments and having engagement with one of the abutments, a washer between the escutcheon member and the other abutment member, said washer having a pair of diametrically positioned lugs extending from one side thereof to engage one of the members to form pivots about which the escutcheon may rock in one plane, said washer being also provided with recesses on its opposite side intermediate the lugs, and projections on the other members seated in said recesses and forming pivots about which the escutcheon may rock in a plane located at an angle to the first plane.

13. In a device of the character described, a door handle having a spindle, spaced abutments on said spindle, an escutcheon between said abutments having engagement with one of the abutments, means between the escutcheon and the other abutment having pivotal connection with the escutcheon in one plane and pivotal connection with the abutment in another plane located at an angle to the first plane, a movable locking bolt carried by the spindle, key controlled means for operating the bolt, and means on the escutcheon to cooperate with the bolt to lock the spindle against turning movement.

14. In a device of the character described, a door handle having a spindle, spaced abutments on said spindle, an escutcheon between said abutments having engagement with one of the abutments, a member between the escutcheon and the other abutment, said member having a pair of diametrically positioned lugs extending from one side thereof to engage the abutment to form pivots about which the member may rock, said member being also provided with recesses on the other side intermediate the lugs, projections on the escutcheon seated in said recesses and forming pivots about which the escutcheon may rock, a transversely movable locking bolt mounted in the spindle, and key controlled means in the spindle for operating the bolt, said escutcheon being provided with recesses to receive the end of the bolt to lock the spindle against turning movement.

In testimony whereof I affix my signature.

JOSEPH GOODMAN.
